UNITED STATES PATENT OFFICE.

JOHN McMYLER, OF CLEVELAND, OHIO, ASSIGNOR TO THE McMYLER INTERSTATE COMPANY, OF BEDFORD, OHIO, A CORPORATION OF OHIO.

CAR-DUMPER.

1,009,331.

Specification of Letters Patent. Patented Nov. 21, 1911.

Application filed March 31, 1911. Serial No. 618,201.

To all whom it may concern:

Be it known that I, JOHN McMYLER, a citizen of the United States, residing at Cleveland, in the county of Cuyahoga and State of Ohio, have invented a certain new and useful Improvement in Car-Dumpers, of which the following is a full, clear, and exact description.

This invention relates to improvements in car dumpers and especially to an attachment or mechanism for preventing discharge of material from a car until after the latter has been tilted or turned to the desired position, or until the tilting movement is substantially completed.

In a well known form of car dumper a loaded car is run on to a cradle which is arranged in a suitable tower and is adapted to be raised to a suitable height and then tilted so as to first elevate and then tilt the car and dump the contents thereof into a suitable chute or other receptacle. During the tilting operation, part if not all of the material at the top of the car falls off the car into the chute before the car has been tilted sufficiently to cause the discharge of its entire contents. When carloads of coal are being handled in the car dumper, that portion of the coal which first falls from the car into the chute during the early tilting movements, is usually good coarse coal, and by falling in the manner above described and in its rapid descent down the chute is very much broken and damaged.

The object of the present invention is to provide an improved and effective means for preventing any loss or discharge of the material from the car until after the car has been tilted to the desired or proper position to at once cause the entire contents of the car to be dumped into the chute.

The above object is accomplished by a device arranged and operated in accordance with my invention and comprising a curtain which is of sufficient length to extend from end to end of the car and which is normally supported in the tower above the point at which the car is tilted. This curtain is arranged in a manner such that when the car is raised to the proper height and tilted the car and curtain swing toward each other so that the curtain will, by the movement of the car, be brought against the open top thereof and will be held in that position so as to prevent the discharge of coal or other

material from the car until the latter has been given substantially its full tilting movement, after which the curtain is released and allowed to swing outward or outward and upward so that the contents of the car may then be dumped as an entirety into the chute. As the car and cradle return to normal position, the curtain, which is preferably counterweighted, swings upwardly and inwardly to its normal position. Preferably the curtain has connected to the top thereof counterweighted cables and also has further connections with suitable stationary parts of the tower, this connection being, in the preferred embodiment of my invention, in the form of sets of pivoted links, a set of these links being arranged at each end of the curtain and serving to restrain, to a certain extent, the movements of the curtain, but nevertheless permitting it to assume various positions so that it may accommodate the movement of the car and adapt itself to cars of various heights.

In the accompanying sheets of drawings, Figure 1 is a side elevation of a portion of a well known form of car dumper equipped with my invention, certain parts being broken away and other parts being shown somewhat conventionally, the curtain being in its normal upper position. Fig. 2 is a partial front view of the same looking toward the left of Fig. 1, certain portions being broken away and the cradle being raised somewhat from the position shown in Fig. 1. Fig. 3 is an enlarged sectional detail view showing particularly the latch or catch mechanism by which the bottom portion of the curtain is attached or temporarily connected to the cradle of the car dumper and showing also the mechanism for preventing the connection between the curtain and cradle being established if, for example, it is desired to dump only a portion of a load instead of the entire load. Fig. 4 is a side elevation, with parts broken away, of the upper portion of a chute, the cradle and car carried thereby and the curtain, this view showing the start of the tilting operation and showing the cradle about to connect on to the curtain. Fig. 5 is a similar view showing the position of the cradle, car and curtain after the cradle has been turned through nearly an angle of ninety degrees. Fig. 6 is a view of the same with the cradle tilted still further and in the position at

which the curtain is about to be released. Fig. 7 is a similar view after the curtain has been released and showing the contents being dumped from the car.

5 In the drawings, 10 represents the usual tower or structure, 11 represents the cradle and 12 a car which is clamped to the horizontal platform of the cradle by suitable clamping means 13. Both the tower and 10 cradle may be of any suitable construction, and as they are common and well known, need not be described in detail. It will be understood, however, that the cradle is elevated by cables 11^a connected to suitable 15 hoisting mechanism (not shown) until a jaw 11^b carried by the cradle engages a pin 11^c carried by a front cross beam to be referred to later; and after the engagement of the jaw of the cradle with the pin, the 20 cradle together with the car are turned or tilted about the pin as an axis so as to dump the contents of the car. The contents of the car 12 is adapted to be dumped into a chute or other suitable receptacle 14 which, as in 25 the customary manner, is pivoted at its upper end to a beam 16 which is supported between the front vertical columns 10^a and 10^b (see Fig. 2) of the tower 10. At opposite ends of the beam 16 are the usual aprons 30 17 which are designed to guide the material into the open end of the chute. In the usual construction of car dumpers of the type illustrated, the beam 16 is arranged to be adjusted vertically so as to adjust the vertical height to which the cradle is to be elevated and the point at which the material is dumped into the chute.

It will be seen that when the cradle has been so tilted that the car is turned through 40 an angle slightly greater than that shown in Fig. 4, the material at the top of the load in the car will fall from the car and will drop some distance before striking or entering the chute, and if coal is being unloaded, 45 this coal will be broken and damaged in the manner previously stated. It will also be seen, that, unless means are provided for preventing the early discharge of the material from the car, the discharge will be 50 more or less scattered and continuous throughout nearly the entire tilting movement of the car or until the car reaches the position shown in Fig. 6, which is its full discharging position. To avoid this occurrence and, in fact, to provide means whereby 55 the discharge is almost entirely prevented until the car reaches the position shown in Fig. 6, my invention, in the way of an attachment, has been provided and will now be described.

Arranged above the upper open end of the chute and above the point about which the car and cradle are tilted and supported substantially in line with the front plane of the 5 tower, is a curtain 18 comprising a main

front or forward portion 18^a which, when the curtain is in normal position, is substantially vertical and is of a length such as to extend from one end of the car to the other, and end pieces 18^b extending rearwardly from the portion 18^a and adapted to overlap the ends of the car. This curtain is normally held in the position shown in Fig. 4 or in its uppermost position by a number of counterweighted cables 19 which are connected at distributed points along the top edge of the curtain, and from the curtain extend upwardly over sheaves 20 at the top of the tower, thence rearwardly and over sheaves 21, and thence downwardly along the rear side of the tower, the ends of the cables having counterweights 22. At its ends the curtain is also connected to stationary points of the structure, and preferably to extensions 23 of the aprons 17 or other suitable parts connected to the cross beam 16, and preferably these connections are in the form of links 24, the curtain being connected at each end and near the top thereof to one of the members 23 by links 24^a and 24^b which are parallel and of equal length, and by shorter links 24^c and 24^d which are parallel and of equal lengths. Each of the connections 24, therefore, consists of a parallelogram of pivoted links. 95 While I do not consider the parallelogram of links essential, I find that it is very suitable and efficient as it permits the desired movements of the curtain forwardly and downwardly with the car or upwardly to its normal position after the curtain has been released from the car, and also permits the curtain to adapt itself to cars of various heights.

Arranged along the bottom of the curtain 18 are a series of pivoted or swinging latches 25, each of which is provided with an open notch or slot 25^a and at its lower end with a roller 25^b for the purpose to be referred to presently. The cradle and curtain are designed to be temporarily connected together at the beginning of the tilting movement of the cradle so that the curtain may lie over or along the open top of the car, in a manner illustrated in the drawings, by means of these catches and by a series of pins 26 which may be provided with rollers. In this case the pins 26 are provided at the top or upper end of the car clamping means 13, previously referred to, and are arranged opposite or in line with the several catches 25. These catches 25 and the pins 26 are so arranged that after the cradle has been raised to the desired height and shortly after the beginning of the tilting movement of the cradle, the pins drop into the open notches 25^a of the catches and thence as the tilting movement continues the curtain is pulled downward and outward and the car and curtain move toward each other so as to cause the curtain 130

to cover or lie along the open top of the car. As the tilting movement continues, the curtain precedes the car and cradle, the parallelogram of links spreading, readily permitting this movement. The curtain thus remains firmly attached to the cradle so as to prevent the discharge of material from the car and serves as a retainer until the cradle reaches its dumping position, at which point 5 the curtain is released, and this I prefer to be done automatically. This is accomplished at substantially the end of the tilting movement by the engagement of the rollers 25^b at the lower ends of the catches with the bottom of the chute or with suitable members 15 27 provided for this purpose and by the consequent disengagement of the catches with the pins 26. As soon as this occurs the contents of the car forces the curtain outwardly 20 and away from the car so that the contents may be dumped as a whole and at once into the chute. As the car and cradle are returned to their normal upright positions the curtain is restored to its normal position by 25 the counterweights 22. In this manner the breakage of coal is very materially lessened. In some instances it may not be desirable 30 to dump the entire contents of the car at one time as, for example, when it is desired to dump a portion of a carload into one hatch of a vessel and other portions in other hatches. In order that this may be done, I have provided means for preventing the curtain being attached to the cradle so as not 35 to be pulled downward with the car, and this means is preferably in the following form or embodiment.

Along the front of the curtain and near the bottom thereof is a rock-shaft 28 which 40 is designed to be turned by means of a line 29 extending to the operator and passing about a sheave 30 arranged above the rock-shaft 28, and having its end connected to an arm 31 which is fixed to the rock-shaft at 45 the center thereof. This rock-shaft has also secured thereto a series of arms 32 which extend downwardly and are arranged at an angle with respect to the arm 31, these arms 32 being arranged above the various catches 50 25. Each of the catches 25 has pivotally supported adjacent thereto and preferably on the same pivotal axis therewith, a lever 33 with its forward end counterweighted and provided at its rear end with a pawl 33^a 55 which, when the forward end of the lever is raised, is adapted to extend over and close the open notch or slot in the corresponding catch 25 in which the pin 26 of the cradle is normally adapted to enter. The levers 33 60 are arranged directly beneath the arms 32 fixed to the rock shaft 28 and are connected to said arms by short connecting means 34. Thus when it is desired to prevent the catching and connection of the cradle with the 65 curtain, the operator, by pulling on the

line 29, rocks the rock-shaft 28 so as to shift the levers 33 and cause the pawls 33^a to prevent the pins 26 on the cradle entering the notches of the catches 25. This mechanism permits the operator at will to prevent the use or operation of the curtain so that the contents of the car or any desired quantity of it may be dumped in the usual manner. 70

Having described my invention, what I 75 claim is:

1. In combination in a car dumper, a tower, a cradle adapted to be moved upward in said tower and tilted so as to dump the contents of a car, a receptacle arranged to receive the contents of the car, and a curtain yieldingly supported in the tower above the point at which the cradle is tilted and movable downwardly and outwardly with the car and cradle along the open top of the 80 car so as to prevent material being discharged from the car until the latter has been tilted a certain amount. 85

2. In a car dumper, a tower, a cradle adapted to carry a car upwardly in the tower 90 and at a certain elevation to tilt the car, a chute arranged to receive the material dumped from the car, a curtain yieldingly supported above the chute and above the point at which the cradle is tilted, and means 95 whereby a connection is made between the curtain and one of the tilting parts so that the curtain will be moved downwardly and outwardly with the car along the open top thereof. 100

3. In a car dumper, a tower, a cradle adapted to carry a car upwardly in the tower and at a certain elevation to be tilted so as to dump the contents of the car, a receptacle arranged to receive the contents of the car, a curtain supported at the front of the tower above the receptacle and above the point at which the cradle is tilted, and latching means arranged to connect the lower portion of the curtain with a part on the cradle so that the curtain will be moved outwardly with the car along the open top thereof so as to prevent material dropping from the car during a portion of the tilting movement. 105 110

4. In a car dumper, a tower, a cradle adapted to carry a car upwardly in the tower and at a certain elevation to be tilted so as to dump the contents of the car, a receptacle arranged to receive the contents of the car, a curtain supported at the front of the tower above the receptacle and above the point at which the cradle is tilted, and latching means arranged to connect the lower portion of the curtain with a part on the cradle 120 125 so that the curtain will be moved outwardly with the car along the open top thereof so as to prevent material dropping from the car during a portion of the tilting movement, and means for causing the release of 130

the curtain when the car has been tilted a certain amount.

5. In a car unloader, a tower, a cradle adapted to carry a car upwardly in the tower and at a certain point to be tilted so as to cause the contents of the car to be dumped therefrom, a receptacle arranged to receive the contents of the car, a curtain arranged in the forward portion of the tower above the receptacle and above the point at which the cradle is tilted, counterweighted cables connected to the top of the curtain tending to pull the same upwardly, and means arranged to form a temporary connection between the curtain and one of the tilting parts so as to cause the curtain to be moved downwardly and outwardly with the car along the open top thereof, and means for breaking said connection to release the curtain so as to permit the contents of the car to be dumped into the receptacle.

6. In a car unloader, a tower or structure, a cradle adapted to elevate a car in said structure and at a certain point to be tilted so as to tilt the car and cause the contents thereof to be discharged therefrom, a receptacle arranged to receive the contents of the car, a curtain normally supported in an upright position above the receptacle and above the point at which the cradle is tilted, counterweighted cables connected to the top of said curtain, means comprising a plurality of links connecting the curtain to said structure, and means for connecting the curtain with one of the tilting parts.

7. In a car unloader, a tower structure, a cradle adapted to carry a car upwardly in said structure and at a certain point to be tilted so as to cause the contents of the car to be dumped therefrom, a receptacle arranged to receive the contents of the car, a curtain normally arranged in upright position at the front of the structure above the receptacle and above the point at which the cradle is tilted, counterweighted cables connected to the top of the curtain, sets of pivoted links connecting the upper end portions of the curtain to points of the structure below the curtain, and means for temporarily fastening the lower portion of the curtain to the cradle comprising catches pivotally supported on the lower portion of the curtain and depending therefrom, and devices on said cradle arranged to engage said catches when the car is being tilted.

8. In a car unloader, a tower structure, a cradle adapted to carry a car upwardly in said structure and at a certain point to be tilted so as to cause the contents of the car

to be dumped therefrom, a receptacle arranged to receive the contents of the car, a curtain normally arranged at the front of the structure above the receptacle and above the point at which the cradle is tilted, means for temporarily fastening the lower portion of the curtain to the cradle comprising catches pivotally supported on the lower portion of the curtain, and devices on said cradle arranged to engage said catches when the car is being tilted, and means for preventing the engagement of said means on the cradle with the catches on the curtain.

9. In a car dumper, a tower, a cradle adapted to elevate a car in the tower and to be tilted so as to dump the contents of the car therefrom, a chute supported at the front of the tower and arranged to receive the contents of the car, a curtain normally supported at the front portion of the tower above the chute and above the point at which the cradle is tilted, said curtain comprising a portion adapted to extend the length of the car from one end thereof to another, counterweighted cables connected to the top of the curtain and tending to pull the same upwardly, and means for forming a temporary connection between the curtain and the cradle comprising catches pivotally supported on the lower portion of the curtain, and means on the cradle adapted to engage in said catches whereby when the cradle is tilted the curtain is moved downwardly and outwardly with the car and cradle along the open top of the car, said catches having portions which engage stationary parts of the chute when the car has been tilted to a certain position so as to cause the catches to be rocked to release the curtain and permit the contents of the car to be dumped into the chute.

10. In combination in a car dumper, a tower, a cradle adapted to be moved upward in said tower, and tilted so as to dump the contents of a car, a receptacle arranged to receive the contents of a car, and a curtain yieldingly supported in the tower and movable downwardly and outwardly with the car and cradle along the open top of the car, so as to prevent material being discharged from the car until the latter has been tilted a certain amount.

In testimony whereof, I hereunto affix my signature in the presence of two witnesses.

JOHN McMYLER.
